UNITED STATES PATENT OFFICE.

ALMA N. NICKERSON, OF STONEHAM, MASSACHUSETTS, ASSIGNOR TO JOSEPH H. McNEIL, OF SAUGUS, MASSACHUSETTS.

ENGINE.

1,260,939.

Specification of Letters Patent. Patented Mar. 26, 1918.

Application filed June 16, 1916. Serial No. 104,094.

To all whom it may concern:

Be it known that I, ALMA N. NICKERSON, a citizen of the United States, residing at Stoneham, in the county of Middlesex and 5 State of Massachusetts, have invented an Improvement in Engines, of which the following is a specification.

This invention relates to certain improvements in single-acting steam engines, and 10 has for its object to provide an engine of this character, which may be readily reversed and which will be as efficient when operating to drive the main shaft in one direction, as in the other.

15 A further object is to simplify and improve the means for controlling the steam supply and exhaust in an engine of the type above referred to.

I accomplish these objects by the means 20 shown in the accompanying drawing, in which:—

Figure 1 is a central sectional and partly diagrammatical view of the cylinder and valve mechanism of a reversible engine embodying my invention.

25 Fig. 2 is a central sectional view of the engine cylinder taken at right angles to the section of Fig. 1.

Fig. 3 is a cross section at the line 3—3 30 of Fig. 2.

Figs. 4 to 9 are section views showing different positions of the piston and valve mechanism.

Figs. 10 and 11 are central sectional views 35 at right angles to each other, of the cylinder of an engine of the non-reversible type, embodying a feature of my invention.

Figs. 12 and 13 are similar views, partly in elevation.

40 Fig. 14 is a detail view illustrating the application of automatic governing mechanism.

While I have only shown the application of the invention to a single cylinder, it will be understood that it is intended to be applied to an engine having at least two cylinders, and may be applied to engines having a still greater number of cylinders, but such additional cylinders have not been shown, as this would involve mere duplication.

45 Referring to Figs. 1 to 9 of the drawings, the cylinder 1 is provided with a single-acting piston 2, having a connecting rod 3 directly connected thereto and to the crank 4 of the main driving-shaft 5, of the engine.

The connecting rod is directly connected to the piston by a cylindrically-shaped head 6, which is mounted to oscillate in the piston and has a pair of ports or passages 6^a, 6^b therein, which are adapted to be brought 60 into and out of register with passages 2^a, 2^{a'}, and 2^b, 2^{b'}, respectively, of the piston as hereafter explained, said passages 2^a and 2^b leading from the sides of the piston, at opposite points, to the head 6, and said passages 2^{a'} and 2^{b'} leading from said head 6 to the working face of the piston.

65 The cylinder is provided with oppositely disposed steam inlet ports 1^a and 1^b, which are connected to steam inlet pipes 7 and 8, respectively, and is also provided with an exhaust chamber 1^c, which opens to the interior of the cylinder through port 1^d, and to which an exhaust pipe 9 is connected. The inlet pipes 7 and 8 are connected to opposite ends of a valve casing 10 in which a hollow piston valve 11 is arranged, said valve having an annular groove 11^a formed therein midway thereof and having suitable operating means, as the connecting rod 12 70 and hand lever 13, located at one end of the valve casing, a steam supply pipe 14 being connected to the opposite end thereof, and a branch pipe 15 being connected to the middle portion thereof and to the exhaust pipe 9. 75

Opposite portions of the piston are provided with longitudinal grooves in which sliding cut-off valves 17 and 18 are mounted each having a port 17^a, 18^a, therein, adapted and arranged to be held in register with the inlet ports 1^a, 1^b, respectively, and with the outer ends of the piston passages 2^a, 2^b, respectively. Each valve 17 and 18 is provided with suitable means for adjusting it longitudinally, the particular means shown 80 comprising a post 19, 20 mounted in the valve and connected by a link 21, 22 to a hand lever 23, 24, which is adapted to be locked in different positions of adjustment.

85 As will hereinafter appear, the parts may be adjusted to cause the engine to be driven in either direction, and in Figs. 1 to 9 the parts are shown as adjusted in the position to cause the main shaft to be driven in the direction of the arrow of Fig. 1. When 90 thus adjusted, the sliding valve 18 will be moved to its outermost position, so that the inner end of its port 18^a will be in register with the inner end of the port 1^b, and the valve 17 will be adjusted inwardly to some 95 100

105 110

point, according to the position at which the steam supply is to be cut off, as will be hereinafter explained.

When the piston valve 11 is in its middle position, it will close both ports leading to the steam supply pipes 7 and 8, and, when it is desired to admit steam to the pipe 7, the lever 13 is moved inward so that steam will pass thereto through the hollow valve 11, and by this movement, communication between the pipe 8 and branch pipe 15 is established through the annular space 11^a, so that port 1^b is opened to the exhaust pipe 9.

In Figs. 1 and 4, the piston is shown in its innermost position, in which position the passage 2^a therein is in open communication with the port 17^a of the slide valve 17, and the port 1^a of the cylinder, to which the supply pipe 7 is connected, so that, when the piston valve 11 is open, the passage 2^a will contain steam under pressure. In this position, however, the inner end of the passage 2^a will be practically closed by the head 6, but, as best shown in Fig. 4, the ends of the passage 6^a therein are so arranged that when the connecting rod 3 is moved slightly to the right, by the passing of the crank beyond the dead center point, communication will begin to be established between the passages 2^a and 2^{a'}, through the passage 6^a, in the head, so that steam will be immediately admitted to the working face of the piston; the passageway thereto being fully open as soon as the piston has moved outwardly a short distance, as shown in Fig. 5. It may be noted that this exact timing is not essential, as steam may be admitted either at a slightly earlier or later time. As the piston moves outwardly, connection between the passages 2^a and 2^{a'} is maintained, but the outer end of the passage 2^a soon begins to pass beyond the outer end of the port 17^a, of the valve 17, so that, when the piston has, for example, half completed its stroke, the entrance to said passage 2^a will have passed beyond the port 17^a, as shown in Fig. 6, causing the steam supply thereto to be cut off, and the remaining portion of the outward stroke of the piston to be made under the expansive force of the steam. As the piston nears the end of its outward movement and the steam in the cylinder has expanded to atmospheric pressure, the working face of the piston will be carried beyond the exhaust port 1^a, so that the interior of the cylinder will then be opened to the exhaust during the remainder of the outward movement of the piston, to the position of Fig. 7, and also during its corresponding return movement, suction and compression during this portion of the piston travel being thus prevented.

As the piston face passes said port 1^a, on the return movement, as shown in Fig. 8,

the head 6 will be turned until the passage 6^b therein is in open communication with the passage 2^b and 2^{b'}, as shown in Fig. 8, so that, beyond this point, the cylinder will exhaust through the passages 2^b and 2^{b'}, 70 through the port 18^a of the valve 18, and through the port 1^b and pipe 8, to the branch pipe 15, through the connecting valve recess 11^a, and to the exhaust pipe 9. As the piston nears the end of its inward movement, the head 6 will be turned sufficiently to close communication between passages 2^b and 2^{b'}, as shown in Fig. 9, so that compression will take place during the remainder of the inward movement. The 80 operation above described will then be repeated.

The engine may be driven in the opposite direction by reversing the relative positions of the slide valves 17 and 18, and moving 85 the inlet valve 11 to its opposite position, so that steam will be admitted to the passage 8 which is connected to the port 1^b, and the passages 2^b and 2^{b'} will become supply passages and the passages 2^a and 2^{a'} will 90 become exhaust passages, being connected to the pipe 9, through pipe 7, valve casing 10, and branch pipe 15, and the operation being otherwise precisely the same as that already described, and its operation on the 95 reverse being as efficient as its operation on the forward motion, this arrangement being especially advantageous for marine work, and for motor-driven vehicles.

Engines employed for the above purpose 100 constantly have an engineer in attendance, and frequently carry, under normal conditions, a constant load, so that the point of cut-off is not, and does not need to be under automatic control.

In Figs. 10 to 14, the application of a feature of my invention to a stationary engine, which is adapted to be run in one direction, only, is shown. As shown in said figures, the cylinder 25 is provided with a 110 single supply port 25^a, to which the steam supply pipe 7^a leads, and the piston 26 has an inlet passage 26^a opening at one end to said port 25^a, and at the other end to a head 27 having a connecting rod 28 fixed 115 therein, said head also having a port 27^a which, in certain positions of said head, connects the passages 26^a and 26^{a'} to admit steam to the working face of the piston.

A slide valve 30 having a port 30^a, and 120 similar in function and operation and arrangement to the valve 17, is also provided, said valve being preferably operated automatically to vary the point of cut-off by means of any suitable form of speed governor 125 31, as indicated in Fig. 14. The piston 26 is also preferably provided with exhaust passages 26^b, which are arranged to be connected with passages 27^b in the head 27 on the return movement of the piston, said pas- 130

sage 27^b leading to the ends of the head and being in open communication with grooves 27^c in the sides of the piston, said grooves being in open communication with an exhaust chamber 25^b in the cylinder 25.

With this arrangement, the exhaust port in the side wall of the piston may or may not be employed, and the particular location of the exhaust passage is not essential beyond a location which permits an open exhaust during the return movement of the piston. The operation is substantially the same as that already described in connection with the engine of the reversible type, that is, steam is admitted through the supply pipe 7^c and passes through the ports 25^a and 30^a, passage 26^a in the piston, passage 27^a in the head 27, and the passage 26^a in the piston, to the working face of the latter, when the piston is about to move outwardly, and is in the position of Fig. 10. The supply of steam to the working face of the piston is cut off as soon as the end of the passage 26^a passes beyond the port 30^a, in the cut-off valve 30, and the interior of the cylinder is opened to the exhaust port 26^a during the latter portion of its outward stroke, and first portion of its inward stroke. Beyond this portion of the inward movement, the cylinder will be opened to exhaust through the piston passages 26^b, passages 27^b, in the head 27, and the grooves 27^c, in the side of the piston, which latter open to the exhaust chamber 25^d, as indicated in Fig. 11.

I claim:

1. A single-acting steam-engine comprising a cylinder having a cut-off device located in its side wall and provided with a steam inlet port, a piston having an inlet passage therein leading from its side to its working face and arranged to be held in communication, at its inlet end, with said inlet port, during a portion of the piston's travel, an oscillatory valve in said piston having automatic means to move said valve to open and close said piston passage during the reciprocation of said piston, and means to adjust the longitudinal position of said cut-off device to vary the point at which the inlet end of said piston passage is moved out of communication with said inlet port.

2. A single-acting steam-engine, comprising a cylinder having an inlet port in its side wall, a piston having an inlet passage leading from the side thereof to the working face and arranged to be held in communication at its inlet end with said inlet port during a substantial portion of the piston's travel, an oscillatory valve in said piston arranged to open and close said passage, a connecting-rod for said piston arranged to oscillate said valve during the reciprocation of the piston, a cut-off device disposed between said inlet port and the inlet end of

said piston passage and having a port therein arranged to be held in register with said inlet port, and means to move said cut-off device longitudinally of the cylinder to vary the point at which said inlet end of said passage passes out of communication with the steam inlet port, on the outward movement of the piston.

3. A single-acting steam-engine comprising a cylinder having a steam inlet port in its side wall, a piston having an inlet passage therein leading from its side to its working face, automatic means to close said inlet passage during the return movement of the piston and to open it during the outward movement thereof, a valve mounted in the cylinder between the inner wall thereof and the piston and having a passage therethrough arranged to be held in communication with said inlet port at one end and with said piston passage at the opposite end and slidably movable longitudinally of the cylinder, to vary the point of disconnection between its passage and the inlet end of said piston during the outward movement of the latter.

4. A single-acting steam-engine comprising a cylinder having two separate ports in its side wall leading to the interior thereof at corresponding points, a reciprocating piston therein having two inlet passages, each leading from points in its side to its working face, a valve in the piston arranged alternately to open one of said passages and to close the other on the opposite movements of the piston, separate cut-off devices mounted to engage the inner wall of the cylinder for adjustment longitudinally thereof, each having a passage therethrough arranged to be connected at one end with the inlet end of said piston passages to connect said ports and passages throughout different portions of the travel of the piston, and means to connect either of said ports to a source of steam supply or to the exhaust in alternate relation.

5. A single-acting steam-engine comprising a cylinder having two separate ports in its side wall leading to the interior thereof at corresponding points, a piston therein having two inlet passages, each leading from the sides thereof to the piston face, a valve in said piston automatically oscillated on each reciprocation thereof alternately to open one of said passages and close the other on the opposite movements thereof, cut-off devices independently movable to connect said cylinder ports and the entrance ends of said piston passages at different points in the travel of the piston, and valve-mechanism arranged to connect either one of said ports to a source of steam supply, and the other to the exhaust.

6. A single-acting steam-engine comprising a cylinder having two separate ports

4
located at opposite points in its side-wall, a reciprocating piston therein having two inlet passages each leading from corresponding points in its side to its working face, valve-mechanism in the piston arranged alternately to open one of said passages and to close the other on the opposite movements of the piston, means to vary the point of connection of said passages with

5
10 said ports and means to connect either of

said ports to the steam supply and to the exhaust in alternate relation, according to the desired direction of rotation of the engine.

In testimony whereof, I have signed my ¹⁵ name to this specification, in the presence of a subscribing witness.

ALMA N. NICKERSON.
